MAUDE R. STODDARD Inventor

By Conrad A. Deetrich
the ATTORNEY.

UNITED STATES PATENT OFFICE.

MAUDE R. STODDARD, OF NEW YORK, N. Y.

LATCH.

970,661.

Specification of Letters Patent. Patented Sept. 20, 1910.

Application filed December 23, 1909. Serial No. 534,578.

To all whom it may concern:

Be it known that I, MAUDE R. STODDARD, a citizen of the United States, residing at the city of New York, borough of Manhattan, in the county and State of New York, have invented certain new and useful Improvements in Latches, of which the following is a full, clear, and exact specification.

My invention relates to improvements in locks for securing hinged doors or covers to the frames or receptacles to which the same are attached, and said invention has for its object more particularly to provide a simple, efficient and reliable latch having improved fulcruming means whereof the engaging member may be readily attached to, or removed from its supporting member or plate.

Further, said invention has for its object to provide a lock having a resilient member which serves to maintain the movable or locking member in locking position, and which also serves to support said movable or locking member in such manner that the same can be readily detached and removed from its supporting plate or member.

Further, said invention has for its object to provide a lock in which the handle or latch operating member is free at one end and has its said free end guided so as to hold the same against lateral movement or accidental displacement.

Further, said invention has for its object to provide a lock composed of the smallest number of parts possible, and which can be easily and conveniently assembled.

Further, said invention has for its object to provide a lock in which the movable or locking member may be pivotally supported in operative position without requiring the use of a separate or independent pivot pin.

To the attainment of the aforesaid objects and ends, my invention consists in the novel details of construction and arrangement of parts hereinafter more fully described and then pointed out in the claims.

In the accompanying drawings forming part of this specification wherein like numerals of reference indicate like parts, Figure 1 is a perspective view of a portion of a closet and door, showing one form of lock embodying my said invention applied thereto; Fig. 2 is a sectional view of the supporting parts of the latch; the latch and actuating spring being shown in elevation,

the broken lines showing the latch about to engage with its keeper, and the full lines showing the parts in proper locking engagement; Fig. 3 is a similar view showing the manner of releasing or unlocking the latch; Fig. 4 is a front elevation of the face-plate of the latch, and Fig. 5 is a perspective view of the latch-member detached from its face-plate or support.

Referring to the drawings, the lock or latch is shown as comprising a latch-lever 10 which is provided with a detent 11 having its end beveled, so as to enable the automatic locking or engaging of said detent 11 with a keeper or engageable member, such as 12. The latch-lever and the keeper may be of any desirable form. The detent 11 extends through a slot or opening 13 in a face-plate 14. The upper portion of said face-plate 14 forms a fulcrum-member or support for the latch-lever 10, by the engagement of the upper end 15^a of the opening 13, with a recess or notch 16 in the upper edge of said latch-lever. The notch 16 is of such shape and proportion as to permit of the necessary play of the latch-lever upon its fulcrum 15^a.

17 denotes a latch releasing handle, preferably of C-shape, which depends from the outer end of the latch-lever, and is preferably formed integrally therewith. The lower end 18 of said handle 17 is substantially parallel with the latch-lever 10, and is preferably formed in the arc of a circle, of which the fulcruming point of the latch-lever is a center. The said end portion 18 works in a guide-hole 19 in the lower end of the face-plate 14, which guide-hole 19 also extends through a boss 20 upon the outer surface of said face-plate 14.

A coil actuating spring 21 serves to hold the latch-lever in engagement with fulcrum-member 15^a, and said spring 21 also serves to cause the detent 11 of the latch-lever 10 to engage with the keeper 12, and hold the same in locking engagement therewith, as shown in full lines at Fig. 2. The spring 21 is preferably bent or curved, and is maintained in position by means of a curved stud or projection 22 upon the back of the face-plate 14 just below the opening 13 therein, which engages one end of said spring, and by a similar curved stud or projection 23 arranged upon the underside of the latch-lever 10, which engages the opposite end of said spring. It is obvious, however, that the latch-lever may be maintained in proper

operative relation upon the face-plate 14 by any suitable spring or resilient member.

The face-plate of the lock is adapted to be secured to a door, such as 24, by screws or other suitable fastening devices 25, and the door is provided with a suitable recess 26 for the purpose of receiving the latch-lever 10 and the actuating spring 21 therein. As thus constructed, it will be observed that the entire lock consists of but two structural parts held in operative relation by means of an interposed actuating spring. It will also be obvious that the guide-member 20 having the opening 19 therein may be formed separately from the face-plate 14 and secured thereto in any convenient or well known manner. In the present instance, the same is shown integral with the face-plate as a matter of convenience of construction.

The latch-lever with its attached handle and the spring may be readily and quickly assembled and mounted in position upon the face-plate 14 without the use of tools and without requiring skilled labor. This is an important feature since it permits of the latch being taken apart for shipment and storage, and permits of the removal of the latch-lever and its attached handle, to avoid damage or breakage of the lock after it has been attached to any receptacle or article of furniture.

Having thus described my invention, what I claim and desire to secure by Letters Patent is:

1. In a latch, the combination of a plate having two openings, a portion of said plate at one end of one of said openings forming a fulcrum-member, with a latch-lever fulcrumed in said opening and engaged with said fulcrum-member, a handle for said lever guided in the other of said openings, and means acting on said latch-lever to maintain said engagement.

2. In a latch, the combination of a plate 45 having two openings, a portion of said plate at one end of one of said openings forming a fulcrum-member, with a latch-lever fulcrumed in said opening and engaged with said fulcrum-member, a handle for said lever guided in the other of said openings, and spring means interposed between said plate and latch-lever for maintaining said parts in operative relation.

3. In a latch, the combination of a plate 55 having two openings, a portion of said plate at one end of one of said openings forming a fulcrum-member, with a latch-lever fulcrumed in said opening and engaged with said fulcrum-member, a handle for said lever guided in the other of said openings, and a spring, mounted at one end on the inner side of said plate and at the other end bearing on said latch-lever to maintain said engagement.

4. In a latch, the combination of a plate having a pair of openings therein, a latch-lever disposed in one of said openings and extending therethrough, said latch-lever having a notch in its upper edge engaging the plate at one end of said opening, a handle on said latch-lever having a free outer end, and a spring having one end mounted upon said plate and its other end engaged by and bearing upon the underside of said latch-lever to maintain said parts in operative engagement, and a segmental projection upon the free end of said handle extending into the other of the openings in said plate for guiding said handle.

Signed at the city of New York, in the county and State of New York, the thirteenth day of December, nineteen hundred and nine.

MAUDE R. STODDARD.
